United States Patent Office

Des. 233,668
Patented Nov. 19, 1974

233,668

CONTROL UNIT FOR AN ANTENNA ROTATOR

Raymond Kaysen, Glenside, Pa., assignor to
RCA Corporation

Filed July 2, 1973, Ser. No. 375,381

Term of patent 14 years

Int. Cl. D13—03

U.S. Cl. D26—13 C

Fig. 1.

Fig. 2.

Fig. 3.

Fig. 4.

Fig. 5.

FIG. 1 is a perspective view of a control unit for an antenna rotator, showing my design.

FIG. 2 is a right side elevation view thereof, the left side elevation being a mirror image thereof,

FIG. 3 is a back end elevation view thereof,

FIG. 4 is a top plan view thereof, and

FIG. 5 is a front elevation view thereof.

I claim:

The ornamental design for a control unit for an antenna rotator, as shown and described.
